UNITED STATES PATENT OFFICE.

CECIL M. CLARKE, OF CHICAGO, ILLINOIS.

ART OF MANUFACTURING SHEATHING MATERIAL.

1,269,906.

Specification of Letters Patent. Patented June 18, 1918.

Original application filed April 1, 1915, Serial No. 22,443. Divided and this application filed June 18, 1918. Serial No. 104,390.

To all whom it may concern:

Be it known that I, CECIL M. CLARKE, a citizen of the United States, residing at Chicago, in the county of Cook and State 5 of Illinois, have invented a new and useful Improvement in the Art of Manufacturing Sheathing Material, of which the following is a specification.

My present invention, which as to certain 10 features thereof is a division of my co-pending application for United States Letters Patent, Serial No. 22,443, filed April 19, 1915, relates more particularly to a method of producing sheathing material, more 15 commonly used for roofing purposes and generally termed prepared roofing, which is formed of a base, or foundation, sheet of felt or other suitable, durable and absorbent material, treated to a suitable material for 20 rendering it waterproof and having its upper surface coated with an adhesive substance, such as asphaltum, or the like, and with a surface-coating or particles of any suitable material, as for example crushed 25 stone, slate or other similar material, or sand, or the like, applied to and adhering to the adhesive coating, the surfacing-particles being provided of different colors or 30 different physical characteristics and applied to such positions on the coating that a design is produced thereon.

My object, generally stated, is to provide 35 an improved method whereby sheathing material of the general character above stated and with the surfacing-particles arranged in substantially the same plane, and preferably with the material of one color or characteristic merging into the material adjacent to it and of a different color or characteristic to produce a soft, as distinguished 40 from a sharp, line of demarcation between the different sections of the surfacing forming the design, may be produced economically and rapidly.

Referring to the accompanying drawings, 45 Figure 1 is a diagrammatic view in elevation of a desirable form of apparatus suitable for carrying out my new method; and Fig. 2, an enlarged plan section taken at the line 2 on Fig. 1 and viewed in the direction of the arrow, this section being taken through the devices for applying the granular particles

to the asphaltum coating on the foundation sheet, and showing different portions of the sheet, the separated section of the sheet 55 representing the condition presented by it after the non-adhering particles are removed from the sheet.

Referring to the apparatus illustrated and which is of a very desirable form for practising my invention, the general characteristics of this apparatus are the same as those of machines now commonly employed for the production of prepared roofing of the variety involving the foundation sheet and a 60 surfacing of crushed slate, sand, broken stone or the like, and therefore a diagrammatic representation of the apparatus, excepting as to its novel features, will suffice. In the apparatus shown the sheet of material, shown as a strip, as for example, of felt, which is to form the foundation sheet of the finished sheathing material, is represented at 3 and, in practice, is provided in a roll as at 4, the roll being supported to permit the sheet to be unwound therefrom, in any suitable manner, as by journaling it on the shaft represented at 5. The sheet 3 passes over a roll 6 journaled in any suitable manner, thence downwardly into a tank 7 and 65 under rollers 8 and 9 journaled therein near the bottom of the latter, and upwardly over a heated drive roller 10 journaled in the top of the tank and driven in any suitable manner. The tank 7, in accordance with common practice, would contain any suitable waterproofing, readily absorbed liquid, as for example asphaltum, of such character that it will be readily absorbed by the sheet 3. The sheet 3 in passing over the roller 10 70 passes under the heated drive roller 11 journaled in any suitable manner and driven in any suitable manner, these rollers serving to remove from the sheet 3 the surplus liquid carried up thereby from the tank. The 75 sheet 3 passes beneath a tank 12 which contains any suitable adhesive waterproof coating of relatively thick constituency, the material usually employed being asphaltum. The material from the tank 12 discharges 80 upon the upper surface of the sheet 3 through a valved outlet 13 which extends across the machine practically throughout the width of the sheet 3 and serves to apply

thereto a coating of the asphaltum or other material used. From this point the sheet 3 passes heated squeeze rollers 14 and 15 which operate to spread the asphaltum supplied to the sheet, to produce a uniform coating thereon in accordance with common practice. The sheet 3 then passes under a device for applying to the asphaltum coating on the sheet 3, particles such as crushed stone, slate, sand or other suitable material, which, preferably, together with other particles afterward applied to the sheet, form the surface-coating. This device in the form shown, comprises a hopper 16 supported in any suitable manner to extend above the sheet 3 and of a width substantially equal to the width of the said sheet, as shown in Fig. 2. The lower end of this hopper, which is open, is provided with a pair of inwardly extending flanges 17, which reach short of each other as illustrated and which form guides for a pair of edgewise opposed slides 18 and 19 which lie in the same plane and form a bottom for the hopper 16. These slides 18 and 19 are so constructed that by shifting them relative to each other, material from the hopper 16 will be caused to be spread upon the upper, coated, surface of the sheet 3, to form a skeleton design thereon; these slides, to serve this purpose, being preferably each formed at the edge thereof which opposes the other slides, with a series of recesses 20 equidistantly spaced apart, so that when the slides 18 and 19 occupy a certain position relative to each other, as illustrated in Fig. 2, the intermediate recesses 20 in the opposed slides will register with each other. Coöperating with the slides 18 and 19 is mechanism for reciprocating them in opposite directions, the mechanism shown, and which is merely illustrative of one kind of mechanism which may be employed for this purpose, comprising a shaft 21 driven in any suitable manner (not shown), and equipped with a crank pin 22 connected with a rocker-arm 23 by a link 24 pivotally connected with the pin 22 and with a pin 25 on the arm 23, this arm being connected with a shaft 25^a supported in journaled position in any suitable way. The arm 23 is provided with extensions 26 and 27 extending at angles thereto and provided with pins 28 and 29, respectively, arranged eccentrically of the shaft 25^a and at opposite sides thereof, these pins forming pivot connections for pitmen 30 and 31 pivotally connected at their other ends to pins 32 and 33 on the ends of the slides 18 and 19, respectively.

60 It will be understood from the drawing and the foregoing description that when the shaft 21 is rotated the arm 23 is rocked back and forth, thus causing the slides 18 and 19 to be reciprocated in opposite directions.

65 As the sheet 3 passes along under the hopper

16, the movement of the slides 18 and 19, as stated, will cause material to discharge from the hopper 16 through the recesses 20 onto the asphaltum coating of the sheet 3, to produce the skeleton design substantially 70 as shown in Fig. 2, wherein the bands of surfacing extending obliquely of the sheet 3 and in intersecting relation, are represented at 34, and the sections of asphaltum coating remaining uncovered being represented 75 at 35.

After passing under the hopper 16 and the operating mechanism therefor, just described, the sheet 3 passes beneath a suction device represented at 41, for removing from 80 the sheet 3 excess material deposited thereon from the hopper 16, as stated. These suction means may be of any suitable construction, those illustrated involving a suction-head 42, which is supported in a manner 85 (not shown), to extend transversely of the sheet 3 and slightly above the latter, but sufficiently close thereto to cause the excess surface-coating on the sheet 3 to be removed from the sheet under the action of suction 90 applied to the head through a pipe 43 connecting with the latter and leading to a vacuum pump or any other suitable suction-producing device (not shown).

After passing beyond the suction device 95 41, the sheet 3 passes beneath a hopper 36 provided with a discharge slot 37 along its lower edge, the hopper 36 extending practically the entire width of the strip 3 and its outlet 37 extending practically throughout the length of the hopper. This hopper is provided for receiving and spreading the particles of material which are to form the surface-coating of the finished sheathing material, between the bands 34. The sheet 3 100 in passing under the hopper 36 has spread over its entire surface, the material contained in the hopper 36; and from this hopper the sheet 3 passes under and over pressing and drying or cooling rolls 37, 38, 105 39 and 40, journaled in any suitable manner to rotate. In passing from the roll 37 to the roll 38, all of the non-adhering surfacing material falls from the sheet 3; and during the passage of the sheet along the rolls 37 to 40, inclusive, the surfacing particles which contact with the asphaltum coating are caused to become partially embedded therein and firmly adhere thereto. While surfacing particles are applied to the sheet 110 3 from the hopper 36 throughout the area of the sheet, the particles supplied from this hopper adhere only to the portions of the asphaltum coating into contact with which these particles are pressed. Thus, the surface-coating of the sheet is caused to present a design formed of particles of different colors, or different characteristics, as shown at the section X of the sheet 3, the sections of surfacing thus provided being disposed 115 120 125 130

substantially in the same plane thus are in the nature of inlays, as distinguished from superposing surfacing-particles upon a previously applied coating of particles of another color or having other characteristics, to form a design. The application to the coated sheet 3, of particles of different colors or having different characteristics, by successive steps and in the manner described, 10 instead of causing the sheet to present sharp lines of demarcation between the sections of coating material formed of particles of different colors or having different characteristics, causes the lines of demarcation to be 15 "soft" inasmuch as the material of different colors, or characteristics, where they lie adjacent to each other, do not lie wholly at opposite sides of a line between such sections, but particles forming one section partially cover the particles of the adjacent section, at the adjacent marginal edges of these sections, producing a blending or merging of color along more or less indefinite lines defining these sections, thus producing 20 a design presenting a pleasing appearance to the eye.

The feature of removing the excess of material applied to the sheet 3 to form the first application of the surface coating, represented in the drawing by the bands 34, 30 is desirable because, while there is left on the sheet 3 a sufficient mass of the particles forming the surface-coating, to produce the bands 34, to present the desired color design, 35 the admixture of surfacing-particles forming the belts 34 in excess of those required to produce the desired effect, with the coating material applied to the sheet through the hopper 36, which would prevent the use 40 of this excess material for its original purpose, is prevented.

It will be understood that in accordance with common practice the sheet 3 beyond the roller 40 is engaged by suitable feed mechanism (not shown) for feeding the sheet 3 along the path hereinbefore described to bring it into operative position relative to the various elements of the apparatus hereinbefore explained, and preferably wind it 50 into a roll.

It will be readily understood from the foregoing that patterns of many different forms may be produced on the coated sheet 3. The speed at which the mechanism for reciprocating the slides 18 and 19, operates, 55 relative to the speed at which the sheet 3 travels past the hopper 16, determines the angle at which the intersecting bands 34 extend relative to each other and the straightness of the bands 34 and consequently the shape of the intermediate sections 35. An intermittent movement of the slides 18 and 19 or variation of length of stroke will also serve to vary the shape of the design figure produced on the sheet 3,

in the latter case it being possible to make a pattern wherein the bands of first applied coating material do not contact with each other. In fact, many other different designs may be produced on the sheet 3 by the substitution for the particular mechanism shown in Fig. 2 of other common and well-known mechanical movements, for controlling the operation of the mechanism which discharges the coating material upon the sheet. 70 75

What I claim as new and desire to secure by Letters Patent is:

1. The method of producing surface-coated sheathing material which consists in applying a coating of material to certain portions of an adhesive-coated foundation sheet, removing the excess material from the sheet, and then applying to the unsurfaced portions of the sheet coating material 80 of a color or characteristics differing from the first-referred-to coating material.

2. The method of producing surface-coated sheathing material which consists in applying a coating of material to certain 90 portions of an adhesive-coated foundation sheet to adhere thereto, subjecting the coating thus applied to suction action for removing from the sheet the excess of said coating material, and then applying to the unsurfaced portions of the sheet coating material of a color or characteristics differing from the first-referred-to coating material.

3. The method of producing surface-coated sheathing material which consists in applying a coating of material to certain portions of an adhesive-coated foundation sheet, removing the excess coating from the sheet, applying to the unsurfaced portions 100 of the sheet coating material of a color or characteristics differing from the first referred to coating material, and pressing into firm engagement with said adhesive coating on said sheet, the coating material contacting therewith.

4. The method of producing surface-coated sheathing material which consists in applying a coating of material to certain 110 portions of an adhesive-coated foundation sheet to adhere thereto, subjecting the coating thus applied to suction action for removing from the sheet the excess of said coating material, then applying to the unsurfaced portions of the sheet coating material 115 of a color or characteristics differing from the first-referred-to coating material, and pressing into firm engagement with said adhesive coating on said sheet, the coating material contacting therewith.

5. The method of producing surface-coated sheathing material which consists in directing a continuing stream of coating material upon the adhesive coating of an adhesive-coated foundation sheet to cover less 120 125 130

than its entire surface and during such operation moving said sheet relative to said stream, whereby certain portions of said sheet are covered with the said coating material, thereupon subjecting the coating thus applied to suction action for removing the excess of said coating, and thereafter apply-

ing to the uncovered portions of said sheet, to adhere to said unsurfaced portions only, coating material of a color or characteristics differing from the first-referred-to coating material.

CECIL M. CLARKE.
